UNITED STATES PATENT OFFICE.

ABRAHAM GOLDBERG, OF NEW YORK, N. Y.

ATTACHMENT FOR WEARING-APPAREL.

938,229.

Specification of Letters Patent. Patented Oct. 26, 1909.

Application filed February 23, 1909. Serial No. 479,478.

To all whom it may concern:

Be it known that I, ABRAHAM GOLDBERG, a citizen of the United States, and a resident of the city of New York, borough of Manhattan, in the county and State of New York, have invented a new and Improved Attachment for Wearing-Apparel, of which the following is a full, clear, and exact description.

10 This invention relates to attachments for wearing apparel, and more particularly to an attachment for use in connection with skirts, petticoats, drawers and the like, to alter the waste measurements of the garments, and comprises a member adapted to be inserted in the draw string pocket of the garment, and having a flexible strap permanently associated with the member at one end and adapted to be removably secured at 15 its other end to the member, so that the material of the garment can be gathered and can be held gathered upon the member. Two of the attachments are preferably employed with each garment, and have means 20 for removably attaching one to the other at the placket opening of the garment.

The object of the invention is to provide a simple, inexpensive and durable attachment for use with various kinds of wearing apparel, by means of which the waist dimensions of the garments can be altered to adapt them for use by persons having different waist measurements, which obviates the use 30 of a draw string, which requires no alteration whatever in the garment to permit its use in connection therewith, and which is inexpensive to manufacture.

The invention consists in the construction and combination of parts to be more fully 40 described hereinafter and particularly set forth in the claims.

Reference is to be had to the accompanying drawings forming a part of this specification, in which similar characters of reference indicate corresponding parts in all the views, and in which—

Figure 1 is a rear elevation of a part of a garment showing an embodiment of my invention applied thereto; Fig. 2 is an enlarged elevation of one of the attachments, showing the same removed from the garment; Fig. 3 is an edge elevation of the device showing a part in different position in dotted outline; Fig. 4 is an enlarged partial 50 section of a portion of the device showing a detail; and Fig. 5 is an enlarged edge eleva-

tion of parts of two of the attachments, showing them secured together by means of a hook and eye connection.

Before proceeding to a more detailed explanation of my invention, it should be clearly understood, that the same can be used with different kinds of wearing apparel to vary the waist dimensions of the garments, and thereby to adapt the garment 60 for use by persons of different sizes. By means of the attachment a garment can be gathered at the waist, and can be held gathered. The attachment at the same time provides means for securing the placket 65 edges together, and thus obviates the necessity of the draw string.

Referring more particularly to the drawings, I provide a flat sleeve 10 fashioned from thin sheet metal or any other suitable 70 material, and having the sides inwardly disposed at one end to form stops 11 and therebetween an opening 12. An extension member or shank 13 has an enlarged part 14 slidably located within the sleeve and it is 75 adapted to be projected from the sleeve as is shown most clearly in Figs. 2, 3 and 4. The stops 11 prevent the extension shank from being drawn entirely from the sleeve, as is shown most clearly in Fig. 4. The part 80 14 is of sufficient length to guide the extension shank smoothly within the sleeve and to prevent its binding when being projected or retracted. At the free end, the shank has a 85 button 15, the head 16 of which extends forwardly beyond the stem 17, the latter being 90 suitably curved, and being flush with the rear edge of the head, to permit the body to be drawn easily from the draw string pocket.

At the end remote from the shank extension, the sleeve 10 has secured thereto, in any suitable manner, a member 18 fashioned from folded metal or the like and preferably of angular form so that a part of the member can be secured at the under side of the 95 sleeve, while the remainder extends at right angles thereto. The member adjacent to the sleeve has a bearing 19 in which is loosely mounted an elongated link 20 to which is secured one end of a strap 21. The latter is 100 flexible, and, if so desired, may be elastic. It is partly doubled and has an adjusting buckle 22 of any suitable form, by means of which its length can be varied. At the free 105 end, the strap carries a grip loop 23 of the usual form, having an enlarged entrance opening 24 which has an extended con-

stricted part 25. By means of the loop 23 the strap can be removably secured to the button 15. The member 18 has an opening and thus forms an eye adapted to be engaged by a hook 26 carried by a similar member 27 secured to another sleeve 10. The member 27 has bearings 28 in which is mounted a link 29 which carries a second strap 21. The remaining parts of this form 10 of the attachment are similar to those previously described. It will be understood that with each garment is preferably used a pair of the attachments, one of which has an eye member 18, and the other of which 15 has a hook member 27, so that the attachments can be removably secured together at the placket opening of the garment.

The attachment when in use, has the body which comprises the sleeve 10 and the extension shank 13 inserted in the draw string pocket A of the garment B, at the placket opening of the pocket. The material can be gathered upon the body to adjust the waist of the garment, and when sufficient material 20 has been gathered the grip loop is slipped upon the button, over the material, in the usual manner. To prevent the material from slipping through the grip loop I provide the latter, at the constricted end with 25 an inwardly disposed spur 30 adapted to seat in a recess 31 in the stem of the button. This spur may be sharp pointed or rounded, and is preferably of the latter form, as injury to the material is thereby obviated. 30 The button 15 may be mounted at the end of the shank in any suitable manner, and if so desired, may be formed integral therewith. If so desired, the sleeve may be provided at the inside with a suitable spring member, 35 tending normally to retract the extension shank.

Having thus described my invention, I claim as new, and desire to secure by Letters Patent:

45 1. An attachment of the class described, comprising a body adapted to enter the draw string pocket of a garment, and a strap permanently associated with said body and having a part adapted to attach removably to said body, whereby the garment can be held gathered upon said body.

50 2. An attachment of the class described, comprising a body adapted to be inserted removably in the draw string pocket of a garment, and an elastic strap connected with said body and having a free end adapted to attach removably to said body to hold the material of the garment gathered thereupon.

55 60 3. An attachment of the class described, comprising an extensible body adapted to be inserted in the draw string pocket of a garment, an elastic strap connected near one end with said body, and having means for removably attaching at the other end to said

body when the same is in place within the pocket, whereby the material of the garment can be held gathered upon said body.

4. An attachment of the class described, comprising a sleeve, an extensible shank carried by said sleeve, said sleeve being adapted to be inserted in the draw string pocket of a garment, said shank at the end having a button, and an elastic strap secured permanently at one end to said sleeve, and having a loop adapted to engage said button when said shank is within the pocket. 75

5. An attachment of the class described, comprising an extensible body adapted to be inserted in the draw string pocket of a garment and having at one end a button, said body projecting partly from the pocket and having secured thereto at the projecting end an elastic strap, and a loop connected with said strap and adapted to engage said button 80 to hold the garment material covering said button in position, whereby the garment material can be held gathered upon said body. 85

6. An attachment of the class described, comprising a flat sleeve, a shank slidable 90 within said sleeve and adapted to be projected therefrom, said shank having at the free end a button, said sleeve at the end remote from said shank having a member provided with a link, a flexible strap carried by 95 said link and having at the free end a grip loop adapted to engage said button, said sleeve having stops for limiting the projection of said shank.

7. An attachment of the class described, comprising a flat sleeve having a constricted opening at one end, and having at the other end a member carrying a link, an extension shank having an enlarged part within said sleeve and adapted to engage at edges of 100 said constricted opening to limit the projection of said shank, said shank, at the free end having a button, an adjustable strap carried by said link, and grip loop carried by said strap and having an entrance opening 105 provided with a constricted extension and adapted to engage said button, said strap having an adjustable buckle.

8. An attachment of the class described, comprising a body having a free part adapted to be inserted in the draw string pocket of a garment, a button at one end of said body, an adjusting strap permanently secured to said body at the end remote from said button, said strap being adjustable, and a grip loop carried by said strap and adapted to engage said button. 115 120

9. Attachments of the class described, adapted to be inserted in the draw string pocket of a garment and to project at the 125 placket opening of the draw string pocket, one of said attachments, at the projecting end having an eye, the other of said attachments, at the projecting end having a hook adapted to engage said eye, each of said at- 130

tachments having a strap permanently associated therewith and adapted to engage removably near the end of its attachment remote from the projecting end.

- 5 10. Attachments of the class described, each adapted to be inserted in the draw string pocket of a garment and having means arranged longitudinally at the outside of the pocket for holding the garment
10 material gathered thereupon, said attach-

ments further, having means for removably attaching one to the other.

In testimony whereof I have signed my name to this specification in the presence of two subscribing witnesses.
